Application May 24, 1954, Serial No. 30,635

Term of patent 14 years

(Cl. D47—7)

To all whom it may concern:

Be it known that I, William G. Bley, a citizen of the United States of America, residing at Richboro, in the county of Bucks and State of Pennsylvania, have invented a new, original, and ornamental Design for a Lady's Stocking, of which the following is a specification, reference being had to the accompanying drawing, forming part thereof.

Fig. 1 of the drawing is a perspective view of a lady's stocking as seen from the front, showing my new design; and

Fig. 2 is a fragmentary perspective view of the stocking as seen from one side.

It is to be understood that the stippled portion of the

illustrated stocking contrasts by difference in color or shade from the band and the leg portion of the stocking.

I claim:

The ornamental design for a lady's stocking, as shown and described.
